UNITED STATES PATENT OFFICE.

MARSHALL B. LLOYD, OF MENOMINEE, MICHIGAN, ASSIGNOR TO HEYWOOD-WAKEFIELD COMPANY, OF BOSTON, MASSACHUSETTS, A CORPORATION OF MASSACHUSETTS.

REED-WEAVING MACHINE.

Application filed September 25, 1922. Serial No. 590,377.

To all whom it may concern:

Be it known that I, MARSHALL B. LLOYD, a citizen of the United States, and a resident of Menominee, county of Menominee, and 5 State of Michigan, have invented a certain new, useful, and Improved Reed-Weaving Machine, of which the following is the specification.

My invention relates generally to machines for producing woven reed articles, but relates more particularly to machines for producing reed articles which embody a frame as a part thereof. The term reed fabric, as here used, means a fabric composed of spaced stakes which are relatively rigid and over and under which relatively flexible filler strands are woven, and it includes both the natural reed, fibre reed, and materials having the general characteristics 10 of reed.

The general object of my invention is to provide a machine whereby the production of woven reed articles having frames may be simplified and expedited.

25 I aim also to provide a machine whereby reed fabrics can be woven directly upon the frame of the article, at least in part, thereby eliminating a number of steps hitherto incident to the manufacture of such articles, 30 also resulting in the ability to produce such articles more rapidly and at a lower cost.

My invention consists generally in mechanism of the form, arrangement and co-action of the parts thereof whereby the above 35 named objects, together with others that will appear hereinafter, are attainable; and my invention will be more readily understood by reference to the accompanying drawings which illustrate what I consider, at the 40 present time, to be the preferred embodiment thereof.

In said drawings, Fig. 1 is side elevation of a machine embodying my invention.

Fig. 2 is a perspective view of an article 45 frame with the stakes secured therein.

Fig. 3 is the top view of a machine shown in Fig. 1, the fabric being omitted better to disclose the construction of the machine.

50 Figs. 4 and 5 are enlarged fragmentary views of the stake actuating and filler strand inserting mechanism.

Fig. 6 is a sectional view substantially along the line 6—6 of Fig. 3.

Fig. 7 is a side view of the product produced by the machine.

Fig. 8 is the sectional view substantially along the line 8—8 of Figure 7.

Fig. 9 is a detail view substantially along the line 9—9 of Fig. 6.

In the drawings I have chosen to depict 60 the production of a baby carriage hood, but this it should be understood is by way of illustration and not by way of limitation. A baby carriage hood is usually composed of a plurality of bow shaped wooden members, generally circular in cross section and which diverge from a common point, the amount of divergence depending upon the size or character of the hood to be produced.

65 In Fig. 2, 1 represents one of the hood frame members and suitably secured therein, in spaced relation, will be found a plurality of stakes 2. It is over and under the stakes 2 that the filler strand is to be woven to the end that a woven reed fabric may be produced.

70 The U-shaped frame member 1 with the stakes attached thereto is placed in the machine about to be described with the stakes thereof, extending downwardly into grooves adapted to receive them. The machine, with the article frame member 1 therein and with a portion of the fabric produced is shown in elevation in Figure 1. The end portions of 75 3—3 of the frame 1 extend into openings formed in the upper portions of standards 4—4 that constitute part of the frame of the machine. These standards 4—4 are rigidly fixed to a suitable base not shown. Mounted in brackets 5 and 6 carried by the 80 standards 4—4 will be found shafts 7 and 8 respectively, the shaft 8 having a wheel 11 thereon which is provided with a plurality of ratchet teeth 12 the function of which will appear hereinafter.

85 The shaft 7 is stationary being keyed to the bracket 5. The shaft 8, however, is rotatable in the brackets 6. Keyed to the shaft 8 so that it rocks therewith is a substantially rectangularly shaped plate 13 which is provided along 90 three of its edges with gear teeth forming the gear rack 14. Secured to the plate 13

is a substantially U-shaped plate 15 which, as is well shown in Fig. 6, is formed upwardly as indicated at 16 to provide a housing which accommodates certain parts 5 of a stake manipulating mechanism. The periphery of the plate 15 is provided with a plurality of grooves 17 of such size and so spaced that they are adapted to receive the stakes 2 before referred to. As will appear 10 shortly, in operation the stakes are moved into and out of the grooves 17. Surrounding the plate 13 and somewhat beyond the plane of the stakes will be found a frame portion 18 which, in plan, is U-shaped. The frame 15 18 terminates in the end portions 19 that are fixed to the shaft 8 so that any movement 15 of the shaft 8 causes corresponding movement of frame 18. In the frame 18 there is mounted a plurality of blocks 20, one for 20 each stake of the article to be produced, which blocks are slidable to and from the plane of the stakes. Each block 20 is provided with a guide portion 21 fitted in frame 18 to guide the block in its sliding 25 movement. Each block 20 is also provided with a somewhat vertically disposed groove 22 adapted at times to receive the stakes 2, which block 20 is furthermore normally pressed toward the center plane of the 30 stakes by means of a spring 23. A spring 24 tends to press a pin 25 toward the central plane of the stakes. This pin 25 it will be understood is adapted to project directly into the stake receiving grooves 22 the purpose 35 of which will appear hereinafter. It will be understood that all the blocks 20 are of like construction so that the description of the one just given will suffice for all.

The plate 13 furthermore is provided with 40 a T-shaped slot 26 the path of which is substantially U-shaped (see Figure 3). A roller 27 operates therein, the roller being attached to the upper end of a depending frame member 28. To the lower end of the frame member 28 there is secured a reel 29 on which the 45 filler strand 30 is carried, the filler strand 30 passing upwardly through the hollow portion 31 of the frame 28. The upper end of the portion 31 terminates in a shuttle-shaped 50 portion 32, the operation of which will appear shortly. The frame 18 is embraced by a bracket member 33 which is secured to move with the frame 28. The bracket 33 is provided with a U-shaped portion 34 which 55 slidably engages the frame 18 and carried upon a bracket 35 will be found a filler strand packing wheel 36. For actuating the packing wheel 36 there are a number of pins 37 which are mounted in the frame 18 and 60 which stand upright therefrom.

There remains yet to be described the mechanism for projecting alternate stakes from their normal plane to form a shed for the reception of the filler strand. This 65 mechanism is mounted upon a bracket 38

carried by the frame 28. Upstanding from the outer end of the bracket 28 is a stud shaft 39 which in turn is surrounded by a sleeve 40 the upper end of which terminates in an elliptical cam portion 41. Surrounding 70 the cam portion 41 will be found four radially movable jaws 42, 43, 44 and 45, the jaws 42 and 43 being diametrically opposite and the jaws 44 and 45 being diametrically opposite. The jaws 42 to 45, inclusive, are 75 provided with curved outer faces 46 to 49, inclusive, which, when the blocks are properly positioned are adapted to engage the stakes and cause projection thereof from their normal plane for shed forming purposes.

The jaws 42 to 45, inclusive, are arranged for sliding movement in the upper portion 50 of the wheel 51 which in turn, has gear teeth 52 which mesh with the teeth of the gear rack 14. The gear wheel 51 is keyed to the sleeve 40 so that rotation of the wheel 51 causes like rotation of the sleeve 40 cam 41 and sliding jaws 42 to 45, inclusive. The jaws 42 and 43 are pulled toward the center 90 of the cam by means of the tension spring 53 and the jaws 44 and 45 by means of the tension spring 54. They are thus kept in contact with the outer face of the cam 41, two thereof being always positioned along 95 the major axis of the cam and two along the minor axis. It is thought that the remaining features of the machine will be better understood by a description of its 100 operation.

As before stated, the article frame 1 with the stakes 2 secured therein is placed in the machine, the end portions 3 of the frame being passed through openings in the standards 4, as is well shown in Fig. 3. The frame 1 follows the U-shaped form with the machine and the stakes extend downwardly, normally entering the recesses or slots 17 in the housing part 16 of the plate 15. In starting the machine it will be understood that the frame 18 is relatively close to the frame 1 of the hood. The filler strand 30 is pulled through the end portion 32 of the filler strand inserting means and is suitably 105 passed under one or more stakes. Thereafter, the operator grasps the frame 28 as by means of either or both of the handles 55, 56 and thereby moves all the mechanism connected therewith. This movement causes 110 rotary movement of the jaws 42 and 45, inclusive, and assuming that the direction of movement is as shown in Fig. 5, the jaws 42 and 43 will engage alternate stakes pushing them from their position in the grooves 17 of the housing part 16 and into the aligned openings 22 of the blocks 20. As the shuttle-like portion 32 moves along it represses, successively, the blocks 20 in order 115 to make way for its passage. As soon as the shuttle-like portion 32 has cleared a given 120

block 20, the stake 2 is restored to its normal plane under the action of the thrust pin 25, which is moved by the spring 24. The filler strand 30 is thus intertwined with the stakes 5 in the present instance passing over one stake and under the next. Not only is the filler strand guided into place, but it is also properly positioned or packed, relative to the filler strands of pre-formed fabric. This 10 is accomplished by means of the packing wheel 36 which is actuated by engagement with the pins 37, and which has an angularly disposed face so that in its rotary movement it engages successive portions of the filler strand and moves the same upwardly into place. It will be understood that the mechanism is moved the necessary distance in one direction and then reversed and moved the requisite distance in the other direction, 15 which alternate movement is maintained until all the fabric desired is produced. It should also be understood that when one course of filler strand is inserted the whole mechanism is swung downwardly the thickness 20 of one filler strand in order that the next course may be accommodated. Before swinging the mechanism downwardly a distance equal to the thickness of one filler strand, a pawl 64 on the shaft 7 adapted to 25 be actuated by a handle 63, is released from engagement with one of the teeth on the wheel 11. A downward pressure is then exerted on said mechanism and the pawl 64 is then engaged with the next tooth 12 to hold 30 the mechanism in proper position for inserting the next filler strand. In the article under consideration the filler strand is not in the first instance, passed from one end of the frame to the other, because this is not 35 at all necessary, inasmuch as the mechanism can be reversed at any desired point. While means may be provided for the automatic reversal of the parts, manual means are here shown. When the filler strand inserting portion 32 reaches the end of its travel in the direction shown in Fig. 5, the 40 position of the packing wheel 36 is changed by swinging it to the position shown in Fig. 4, that is to say, the bracket 35 is swung 45 around to the opposite side of the portion 32. The nut 57 is loosened to permit the swinging movement and tightened to hold the bracket in set position. The next step is to change the position of the jaws 42 to 50 45, inclusive, from the position shown in Fig. 5 to that shown in Fig. 4. This is accomplished by swinging the bracket 38 from the position shown in Fig. 5 to that shown in Fig. 4. This movement will rotate the gear 55 wheel 51 so as to bring the jaws 44 and 45 to their new position so that the swinging movement of the cam only is necessary to thrust them outwardly and permit retraction of the jaws 42 and 43 under the action 60 of spring 53. To swing the bracket 38 lock- 65

ing lever 60 is released, and when the bracket 38 has reached its new position, it is there held by again tightening the locking lever 60.

In order to rotate the cam 41 relative to 70 the jaws 42 to 45, inclusive, the tapering pin 58 is removed and the cam swung as by means of the handle 59. The handle 59 and the cam 41 are rotated counterclockwise, considering the views Figs. 5 and 4, whereupon 75 the jaws 44 and 45 are moved to the outer position shown in Fig. 4 and the jaws 42 and 43 are moved inwardly, this by virtue of the shifting of the major and minor axes of the cam. The springs 53 and 54 as before stated, constantly keep the jaws in contact with the contiguous faces of the cam. After having adjusted the jaws, the tapering pin 58 is replaced. The machine is then ready for reverse movement. 80

The hood, or other article being produced can thus be quickly woven and the product when removed from the machine appears as in Fig. 7. Thereafter it is but necessary to attach the remainder of the article frame, 85 as indicated at 61, if it is an article which requires an additional frame member. The usual hood fixture will then be secured as indicated at 62 in Fig. 7.

Obviously articles of different forms may 90 be produced by simply changing the contour of the machine, i. e. the path that the filler strand inserting means follows.

The many advantages of my machine will be understood by those skilled in the art to 100 which this appertains without further comment. It might be stated, however, that while in the machine here disclosed the frame that carries the slidable members is arranged with swinging movement away 105 from the position in which the article frame is held, it should be obvious that if desired, the machine could readily be formed so that movement away from the position of the article frame would be uniform. That is 110 to say, that the frame could readily be arranged for movement away from the article frame at right angles thereto.

I claim:

1. A machine for the production of a 115 stake and strand fabric embodying therein a frame having a channel therein conforming to a predetermined outline, a plurality of slidable members arranged on said frame at one side of the channel and adapted to 120 receive the stakes normally arranged at the other side of said channel, means operating on alternate stakes only for moving them transversely across the channel toward the associated slidable member, to stagger said 125 alternate stakes with reference to the intermediate stakes which remain in their normal position, means for interweaving a filler strand with said staggered stakes, and means for packing the filler strand. 130

2. A machine for the production of a stake and strand fabric embodying therein a frame having a channel therein conforming to a predetermined outline, a plurality of 5 slidable members arranged on said frame at one side of the channel and adapted to receive the stakes normally arranged at the other side of said channel, means operating on alternate stakes only for moving them 10 transversely across the channel toward the associated slidable member, means for moving said slidable members to stagger said alternate stakes with respect to the intermediate stakes which remain in their normal 15 position and for laying a filler strand between said staggered stakes, and means for packing the filler strand.

3. A machine for the production of a stake and strand fabric embodying therein a frame 20 having a channel therein conforming to a predetermined outline, a plurality of slidable members arranged on said frame at one side of the channel and adapted to receive the stakes normally arranged at the other 25 side of said channel, means operating on alternate stakes only for moving them transversely across the channel toward the associated slidable member, to stagger said alternate stakes with reference to the intermediate 30 stakes which remain in their normal position, means for simultaneously moving said slidable members and for inserting a filler strand between said staggered stakes, and means for packing the filler strand.

35 4. A machine for the production of a stake and strand fabric embodying therein a frame having a channel therein conforming to a predetermined outline, a plurality of slidable members arranged on said frame 40 at one side of the channel and adapted to receive the stakes normally arranged at the other side of said channel, means for yieldingly holding said slidable members in a predetermined position with respect to said 45 channel, means operating on alternate stakes only for moving them transversely across the channel toward the associated slidable member, and means for inserting a filler strand between said staggered stakes and 50 for moving said slidable members laterally of the channel against the action of their yielding holding means.

55 5. A machine for the production of a stake and strand fabric embodying therein a frame having a channel therein conforming to a predetermined outline, a plurality of slidable members arranged on said frame at one side of the channel and adapted to receive the stakes normally arranged at the 60 other side of said channel, means at one side of said channel providing a guiding bearing support for said slidable members, means for yieldingly holding said slidable members with a part thereof within the 65 channel, means operating on alternate stakes

only for moving them transversely across the channel into the associated slidable members, and means for simultaneously moving said slidable members to remove said parts thereof from the channel against 70 the action of their associated holding means and for inserting a filler strand between the staggered stakes.

6. A machine for the production of a stake and strand fabric embodying therein 75 a frame having a channel therein conforming to a predetermined outline, a plurality of slidable members having a guiding bearing in said frame at one side of the channel and adapted to receive the stakes normally 80 arranged in the other side of the channel, spring means associated with said slidable members for normally holding them with a part thereof within the channel, means operating on alternate stakes only for moving them transversely across the channel toward the associated slidable members, means 85 movable in the channel for engaging said slidable members for moving them laterally and at the same time laying a filler strand between said staggered stakes, and a positively actuated means slidable on said frame on the slidable member side thereof and movable with said filler strand laying means 90 for packing said filler strand upon the 95 stakes.

7. A machine for the production of a stake and strand fabric embodying therein a frame having a channel therein conforming to a predetermined outline, a plurality 100 of slidable members having a guiding bearing in said frame at one side of the channel and adapted to receive the stakes normally arranged in the other side of the channel, spring means associated with said slidable members for normally holding them with a part thereof within the channel, means operating on alternate stakes only for moving them transversely across the channel toward the associated slidable members, means 105 movable in the channel for engaging said slidable members for moving them laterally and at the same time laying a filler strand between said staggered stakes, and means 110 slidable on said frame on the slidable member side thereof and movable with said filler strand laying means and including a packing member arranged substantially in the plane of and above the channel for packing said filler strand upon the stakes. 115

8. A machine of the class described for the production of a stake and strand fabric, embodying therein a plurality of slidable members adapted to receive the stakes, means for moving the stakes and said slidable members transversely to stagger the stakes and for inserting a filler strand and a toothed wheel for packing the filler strand. 125

9. A machine of the class described for the production of a stake and strand fabric, 130

embodying therein a frame, a plurality of 5 slidable members carried by the frame and adapted to accommodate stakes, means for moving alternate stakes and said slidable members transversely to stagger the stakes, said means also inserting a filler strand, 10 filler strand packing means, and means carried by said frame for positively actuating the filler strand packing means when the 15 machine is in operation.

10. A machine of the class described for the production of a stake and strand fabric, embodying therein article frame holding means, a plurality of slidable members 15 adapted to receive the stakes, means for moving alternate stakes and said slidable members transversely to stagger the stakes said means also inserting a filler strand and 20 filler strand packing means positioned on one side of the central plane of the stakes.

11. A machine of the class described for the production of a stake and strand fabric, embodying therein a frame, a plurality of 25 slidable members carried thereby and adapted to receive the stakes, means for moving alternate stakes and said slidable members transversely to stagger the stakes said means also inserting a filler strand and 30 filler strand packing means positioned at one side of the central plane of the stakes, said frame carrying the slidable members being mounted for movement away from its starting position.

35. 12. A machine of the class described for the production of a stake and strand fabric, embodying therein a frame, a plurality of slidable members carried thereby and adapted to receive the stakes, means for moving 40 alternate stakes and said slidable members transversely to stagger the stakes and to insert a filler strand between said staggered stakes, and filler strand packing means positioned at one side of the central plane of 45 the stakes and having means projecting toward said central plane, said frame being mounted for swinging movement.

50. 13. A machine for the production of a stake and strand fabric embodying therein, a filler strand inserting member arranged for movement along a predetermined path, a plurality of stake receiving members positioned along one side of said path and capable of a movement transversely thereof, means on the other side of said path for holding a plurality of stakes in spaced relation, means on said last mentioned side of said path and movable with said filler strand inserting member to engage alternate stakes only and for moving them transversely of said path toward said receiving members, said means comprising a rotary member including jaws reciprocable transversely of the said path during the 55 rotation of said rotary member.

14. A machine of the class described for the production of a stake and strand fabric, embodying therein a filler strand inserting member arranged for movement along a pre-determined path, a plurality of stake 70 receiving members positioned for movement in a direction transverse to said path, for moving the stakes transversely to stagger them, said means including a plurality of pairs of jaws arranged for rotation and 75 means for placing two of said jaws in operative position and two in inoperative position.

15. A machine for the production of a stake and strand fabric embodying therein 80 a frame having a channel therein conforming to a predetermined outline, a filler strand inserting member arranged for movement in the plane of said channel, a plurality of stake receiving members yieldingly 85 supported in said frame on one side of the channel for movement transversely thereof, said frame on the other side of said channel having recesses therein normally receiving the stakes, means operating on alternate 90 stakes only for projecting them from their associated recesses toward their associated receiving members, said last mentioned means including a rotative member, a shaft on which said member is mounted and jaws 95 mounted in said rotative member and engaging parts fixed with respect to the shaft for reciprocating said jaws to engage alternate stakes.

16. A machine for the production of a 100 stake and strand fabric embodying therein a frame having a channel therein, a plurality of slidable members located in a plane on one side of said channel, said frame being formed in a plane on the other side of 105 the channel for holding the stakes in their normal spaced relation, means on said last mentioned side of the channel for operating on alternate stakes only to move them transversely of said channel toward said 110 slidable members, means for laying a filler strand between said staggered stakes, and means movable with said filler strand laying means but located in a position above the same for packing the filler strands upon 115 said stakes.

17. A machine for the production of a stake and strand fabric embodying therein a frame having a channel therein, a plurality of slidable members located in a plane on one side of said channel, said frame being formed in a plane on the other side of the channel for holding the stakes in their normal spaced relation, means on said last mentioned side of the channel for operating on alternate stakes only to move them transversely of said channel toward said 120 slidable members, means for laying a filler strand between said staggered stakes, and means slidable on said frame on the other 125 130

6
side of said channel and including a packing wheel and fixed members on said frame with which said wheel meshes to impart a rotary movement thereto and pack said strand upon said stakes.

18. In a machine of the kind described, in combination with a frame, means providing a channel about said frame having a plurality of spaced notches on one side thereof to hold stake members, and a plurality of spring pressed recessed blocks on the other side of said channel, a strand carrying member arranged in said channel and capable of a relative movement with respect thereto, means for moving alternate stakes from said notches on one side of said channel into the recesses in said blocks on the other side of said channel to stagger said stakes so that said strand carrying member may pass between them, and means for packing said strand upon the stake members.

19. In a machine of the kind described, in combination with a frame, means providing a channel about said frame having a plurality of spaced notches on one side thereof to hold stake members, and a plurality of spring pressed recessed blocks on the other side of said channel, a strand carrying member arranged in said channel and capable of a relative movement with respect thereto, means for moving alternate stakes from said notches on one side of said channel into the recesses in said blocks on the other side of said channel to stagger said stakes so that said strand carrying member may pass between them, means in said blocks for ejecting the stake members after said strand carrying member has passed the same, and means for packing the strand upon the stake members.

20. In a machine of the kind described, in combination with a support, a frame mounted thereon, means providing a channel in said frame having a plurality of spaced notches on one side thereof to hold stake members and a plurality of spring pressed recessed blocks on the other side of said channel, a secondary frame movable on said first mentioned frame in a path correspond-

ing to that of said channel, a strand carrying member on said secondary frame adapted for movement in said channel, means on one side of the channel for engaging and moving alternate stake members out of their notches into the recess of associated blocks, to stagger said stake members so that the strand carrying member may pass between them, and means on the other side of said channel for packing the strand on the stake members.

21. In a machine of the kind described, in combination with a support, a frame mounted thereon, means providing a channel in said frame having a plurality of spaced notches on one side thereof to hold stake members and a plurality of spring pressed recessed blocks on the other side of said channel, a secondary frame movable on said first mentioned frame in a path corresponding to that of said channel, a strand carrying member on said secondary frame adapted for movement in said channel, means on one side of the channel for engaging and moving alternate stake members out of their notches into the recess of associated blocks, to stagger said stake members so that the strand carrying member may pass between them, a strand packing wheel on the other side of said channel and means operable in the movement of the secondary frame for imparting a positive packing action to said wheel to pack the strand on the stake members.

22. A stake staggering device comprising in combination with a machine of the kind described, a gear, a sleeve in said gear and having a cam at its top end, a plurality of radially movable jaws arranged in oppositely disposed pairs, slidably mounted on said gear, means urging each pair of jaws into engagement with the cam and means for locking the cam relative to said gears, so that either pair of jaws may be held in an extended position with respect to said gear.

In testimony whereof, I have hereunto set my hand, this 21st day of Sept., 1922.

MARSHALL B. LLOYD.
